Edgar Peet & Co.

UNITED STATES PATENT OFFICE.

CHARLES H. STONEBRIDGE, OF NEW YORK, N. Y.

SLEEPING-BAG.

1,281,693.

Specification of Letters Patent. Patented Oct. 15, 1918.

Application filed June 7, 1918. Serial No. 238,644.

To all whom it may concern:

Be it known that I, CHARLES H. STONEBRIDGE, a citizen of the United States, and residing at New York, in the county of Bronx and State of New York, have invented certain new and useful Improvements in Sleeping-Bags, of which the following is a specification, such as will enable those skilled in the art to which it appertains to make and use the same.

This invention relates to sleeping bags and particularly devices of this class used for outdoor sleeping by soldiers, campers and others, and the object of the invention is to provide a device of this class having parts to be attached or laced, with closure means for sealing said attached or laced portions to prevent the entrance of water or moisture into the bag when extended for use or folded and shipped from place to place; and a further object of the invention is to provide a sleeping bag, one side and the head and foot ends of which are open and adapted to be closed by attaching devices in the usual manner, after which said openings may be sealed, or made watertight by a closure means as above set out.

The invention is fully disclosed in the following specification, of which the accompanying drawing forms a part, in which the separate parts of my improvement are designated by suitable reference characters in each of the views, and in which:

Figure 1 is a plan view of a sleeping bag in its extended position and partially closed;

Fig. 2 a view similar to Fig. 1 but showing the side opening of the bag entirely closed and sealed;

Fig. 3 a plan view of the head portion of the bag showing the side and head openings entirely closed and sealed;

Fig. 4 a transverse section on the line 4—4 of Fig. 1 on an enlarged scale;

Fig. 5 a partial section on the line 5—5 of Fig. 2 on an enlarged scale; and,

Fig. 6 a plan view of the foot end portion of the bag as shown in Fig. 1 and showing a modification.

In Figs. 1 to 5 inclusive, I have shown at 10 the main body of a sleeping bag of the class specified, said body being preferably composed of fibrous waterproof material and the foot end 11 of which is closed while the head end 12 is open, and one side of the body 10 is provided with a longitudinal

opening 13 which extends from the foot end to the head end thereof.

The body 10 is provided longitudinally of the opening 13 with sealing flaps 14 and 15, the foot ends of which are secured together as shown at 16. The flaps are formed integral with the material of the body 10 and are folded outwardly and backwardly onto said body as shown in Figs. 1, 2 and 5, and secured to the body by longitudinal stitchings as shown at 17 and 18 to form a longitudinal pocket 19 and a longitudinal hem 20 on the edge portions of the flaps 14 and 15 respectively. The upper or outer member of the pocket 19 is provided with a plurality of eyelets 21 spaced longitudinally thereof while the hem 20 is provided with a plurality of correspondingly spaced eyelets 22, this construction being clearly shown in Figs. 1, 4 and 5.

Secured in the pocket 19 is a rope or cord 23 which is provided at intervals with loops 24 which pass outwardly through the eyelets 21 in said pocket. The loops 24 are adapted to be passed through the eyelets 22 in the hem 20 and joined together in the manner shown in Fig. 1 for securing the separate sides of the opening 13 together.

Secured between the flaps 14—15 and the body 10 by the stitchings at 17 and 18 are a plurality of spaced straps 25, and after the separate sides of the opening 13 are secured together, as partially indicated in Fig. 1, the flaps 14 and 15 are brought together, as indicated in dotted lines in Fig. 4, and then rolled together as shown in Figs. 2 and 5, after which the straps 25 are tied together to hold the flaps 14—15 in position, and with this construction the opening at 13 is sealed against the entrance of water or moisture.

The head end portion 12 of the body 10 is provided with top and bottom flaps 26 and 27, the top flap 26 being divided centrally as clearly shown in Figs. 1 and 2, and said flaps are formed integrally with the body 10 in the same manner as the formation of the flaps 14 and 15, and are stitched transversely as shown at 28 to form a pocket 29 on the flap 27 and a hem 30 on the flap 26. The pocket 29 is provided with spaced eyelets 31 similar to the eyelets 21, while the hem 30 is provided with eyelets 32 similar to the eyelets 22, and a cord is secured in the pocket 29 and provided at intervals with loops 33 which pass through the eyelets 31 and are also adapted to be passed through

the eyelets 32 in securing the top head portion of the body 10 to the bottom head portion thereof, as will be readily understood.

The head opening 12 when closed in the manner above set out may be sealed by placing the flaps 26 and 27 one upon another and rolling them in the same manner as rolling the flaps 14 and 15 together, and said flaps may be held in their rolled position by straps 34 secured between the flaps 26 and 27 and the bottom 10 in the same manner as the connections of the straps 25 with the flaps 14 and 15 and the body 10. When the side and head openings 13 and 12 of the body 10 are closed and sealed in the manner above set out and as indicated in Fig. 3, the only place that water may possibly enter the sleeping bag is at the point 35 in Fig. 3, where the longitudinal flaps 14 and 15 meet the transverse flaps 26 and 27, but when folding or rolling up the sleeping bag for shipment, or other purposes, the usual head inclosing hood 36 is first folded inwardly upon the top of the body 10 and said body is then rolled or folded from the head end to the foot end thereof which will bring the point 35 within the central portion of the body formed by rolling or folding the bag and therefore it will be readily seen that it will be practically impossible for water or moisture to enter the bag.

It will also be apparent that the sealing means consisting of the flaps 14 and 15 with the longitudinal opening at 13 may be partially closed when the bag is used by the owner for sleeping purposes, especially when the owner desires to use the same on a stormy night, and said sealing flaps may be closed in the manner shown in Fig. 2, or partially so, in the use of the bag as above set out.

In Fig. 6 of the drawing, I have shown the foot end portion 11 of the bag open and provided with top and bottom flaps 26 and 27 of the same form and construction as the corresponding flaps at the head end portion of the body, said flaps being stitched to the body as shown at 28 to form a pocket 29 on the flap 27 and a hem 30 on the flap 26. The pocket 29 is provided with spaced eyelets 31 and the hem 30 with spaced eyelets 32, and a cord is secured within the pocket 29 and provided at intervals with loops 33 passed through the eyelets 31 and also adapted to be passed through the eyelets 32 to secure the top and bottom portions of the foot openings 11 together. It will be understood that the foot opening 11 as shown in Fig. 6 may be closed by rolling the flaps 26 and 27 together and holding them in such position by straps 34.

With the construction shown in Fig. 6 I provide a sleeping bag which is approximately of the same character as a blanket roll and by providing the open foot end portion, the bag may be entirely open for ven-

tilation or other purposes, whenever desired, and this construction will also facilitate the placement of blankets and the like within the bag as well as facilitating the airing of such articles without removing them from the bag, and while I have shown a sleeping bag of specific form and construction and a common means of attaching or connecting the separate side portions of the openings of said bag, my invention is not limited to these details of construction, and changes therein and modifications thereof may be made, within the scope of the appended claims, without departing from the spirit of my invention or sacrificing its advantages.

Having fully described my invention, what I claim as new and desire to secure by Letters Patent, is:—

1. A sleeping bag composed of a body provided with a longitudinal side opening, flaps formed integral with said body at the opposite sides of said opening, means for connecting the separate sides of said opening, said flaps being adapted to be rolled together to provide a water-tight closure for said opening, and means for holding said flaps in their rolled position.

2. A sleeping bag composed of a body provided with a longitudinal side opening and a transverse end opening, flaps formed integral with said body at the opposite sides of said openings, means for connecting the separate sides of said openings, said flaps being adapted to be rolled together to provide a water-tight closure for said openings, and means for holding said flaps in their rolled position.

3. A sleeping bag composed of a body provided with a longitudinal side opening, flaps formed integral with said body at the opposite sides of said opening, said flaps being folded outwardly and backwardly upon the body and stitched thereto to form a pocket and a hem in said body at the opposite sides of said opening, a plurality of spaced eyelets formed in said pocket, a plurality of correspondingly spaced eyelets formed in said hem, a rope secured in said pocket and provided at intervals with loops which are adapted to pass through the eyelets in said pocket and the eyelets in said hem to connect the separate sides of the opening, said flaps being adapted to be rolled together to form a water-tight closure for said opening, and straps secured to the body at the opposite sides of said opening and adapted to be tied together to hold said flaps in their rolled position.

4. A sleeping bag composed of a body provided with a longitudinal side opening and a transverse end opening, flaps formed integrally with said body at the opposite sides of said openings, said flaps being stitched to the body a predetermined distance from

the edge portions thereof to form pockets in one side portion of said openings and hems in the other side portions of said openings, a plurality of spaced eyelets formed in said pockets, a plurality of correspondingly spaced eyelets formed in said hems, ropes or cords secured in said pockets and provided at intervals with loops which are adapted to pass through the eyelets in said 5 pockets and the eyelets in said hems to connect the separate sides of the openings, said flaps being adapted to be rolled together to form a water-tight closure for said openings and straps secured to the body at the 10 opposite sides of said openings and adapted to be tied together to hold said flaps in their rolled position.

5. A sleeping bag composed of a body portion provided with a longitudinal side opening and a transverse end opening, means for closing said side and end openings, and the opposite sides of said openings being provided with means involving flaps adapted to be rolled together to form a water-tight closure for said openings. 20

In testimony that I claim the foregoing as my invention I have signed my name in presence of the subscribing witnesses this 6th day of June 1918.

CHARLES H. STONEBRIDGE.
